FORM HANGER

Filed Jan. 30, 1929

FIG. 2.

FIG. 4.

INVENTOR:
George E. Greenwood
BY
White, Prost & Fayer
ATTORNEYS.

UNITED STATES PATENT OFFICE

GEORGE E. GREENWOOD, OF SAN FRANCISCO, CALIFORNIA

FORM HANGER

Application filed January 30, 1929. Serial No. 336,097.

My invention relates particularly to forms useful in building concrete structures and which are especially adapted for the encasement of structural beams, such as I-beams, 5 for sheathing them in concrete. Devices of this character are disclosed in my co-pending application entitled Concrete form hanger, filed August 21, 1928, and bearing Serial Number 301,033.

10 It is an object of my invention to provide a form hanger which is adjustable for use with a wide range of sizes of beams such as are employed commercially in the construction of buildings.

15 Another object of my invention is to provide a form hanger which may be applied with a standard width of form bottom to encase beams of varying width.

Another object of my invention is to ob- 20 viate inaccuracies in the dimensions of the finished concrete sheath.

An additional object of my invention is to provide a form hanger which is easily removable after the concrete has been poured.

25 Another object of my invention is to provide a form hanger which can be used repeatedly for a number of different sized beams.

The foregoing and other objects are at- 30 tained in the embodiment of the invention shown in the drawings, in which

Fig. 1 is a cross section on a transverse plane of an I-beam to which the form hanger 35 of my invention has been applied.

Fig. 2 is a perspective view of the form hanger shown in the Figure 1 with portions thereof broken away.

Fig. 3 is a transverse section showing a portion of my form hanger having modified 40 details.

Fig. 4 is a transverse section in perspective of an additionally modified form of my invention.

In its preferred form, the hanger of my invention comprises a spacer adapted to be adjustably secured to a beam and to which in turn is adjustably secured a form bottom, the spacer having the functions of properly positioning the form bottom and of prop- 45 erly positioning the form sides as well.

In the modification of my invention disclosed in Fig. 1, there is shown a beam 6 which is of the shape commercially known as an I-beam and which is to be encased, or sheathed in concrete. In different structures, various different shapes of beams are employed and also beams of the same general cross section but with varying flange thicknesses and web thicknesses. It is to be 55 enabled to employ a form hanger without material change with any of the beam sizes and shapes that are apt to be encountered in commercial practice that I provide the structure shown. This preferably comprises a pair of spacers 7 disposed on either side of the beam and contacting the lower face of the lower flanges thereof. As shown in Figs. 1 and 2, these faces are easily made by severing them from channels or other suitable structural shapes which have the requisite rigidity on the web and flanges thereof. For positioning the spacers 7, I preferably provide a hooked bolt 8 passing thru an aperture in the upper flange of the channel and having a threaded end to which a nut 9 is secured for clamping the spacers 7 tightly against the flange of the beam 6. By virtue of this variable connection fixture, 60 it is easily possible to secure tightly the spacers 7 to any one of a number of beams having various flange thicknesses with only the necessity of adjusting the nut 9. As the nut 9 is tightened the spacers 7, which are capable of rotative movement about the axis of the bolt 8, are usually turned in the direction of rotation of the nut. Inasmuch as the spacers are ordinarily severed from a channel on a transverse plane normal to the longitudinal edges of the channel the distance 65 between the edge of the lower flange of the beam 6 to the corner of the spacer is apt to vary. In some instances the corner of the spacer will be brought into direct contact with the forms surrounding the beam which may result in the misalignment of the form or of the beam. This is an undesirable result and in my prior application I show a means for positively holding the spacer 7 in proper relationship. In the present instance, I preferably round or cut in an arcu- 70 75 80 85 90 95 100

ate manner the end of the spacer 7 and thus thru any of the usual pivotal positions, the distance between the edge of the beam flange and of an extreme part of the spacer is exactly the same.

5 Held at a predetermined distance from the beam 6 by means of the spacers 7 is a form bottom 11 which preferably is of sufficient width for a range of different size beams and which preferably is reinforced by a cross member 12 having a pair of longitudinally extending bolt slots 13 therein. For securing the form bottom 11 adjustably to the spacer and thereby positioning it in a predetermined manner with respect to the beam 6, bolts 14 are preferably inserted thru the slots 13 and extend thru the lower flanges of the spacers 7 and terminate within the channel portions thereof. Preferably the terminal ends of the bolts are threaded to receive nuts 16 which are capable of adjustment for properly relating the various parts. Supported by the form bottom 11 and relatively located by the spacers 7 are form sides 17 which are held against the spacers by strips 18 nailed in place and are properly separated at the upper ends by a cross member 19 also nailed in place.

In the form of my invention shown in Figure 3, I preferably provide spacers 21 which are in most respects similar to the spacers 7 shown in Figure 1 but are relatively thick and are tapped in their apertures for receiving the fastening bolts 22 and 23 so as to obviate the use of securing nuts. By simply rotating the hooked bolt 22 and the fastening bolt 23, a suitable adjustment of the spacers 21 with respect to the beam 26 is provided and also a suitable adjustment of the form bottom 27 with respect to the spacer 21 is provided. In other respects, the modification is substantially as shown in Figure 1.

In Figure 4 is shown an additional modification in that the spacers themselves are of slightly different construction although the remainder of the organization is identical. In this instance, spacers 30 instead of being made of commercial shapes such as channels are preferably formed from flat strips severed along arcuate lines 31 and bent upon themselves to enclose a central channel 32. These spacers 21 receive within their channel portions the adjustable fastenings 33 and 34 which secure the hook bolt 36 and the fastening bolt 37 to the form bottom 38 and the beam 39.

With any of the modifications of my invention, the form bottom 11 is preferably assembled with the spacers into a single unit 40 which is hoisted into position below the beam whereupon the hook bolts are put in place and are fastened. It will be appreciated that any width beam will be accommodated by this construction and that after the form bottom 43 is in place the form sides can be installed and

the beam encased in concrete. When the concrete has set, the form sides are removed and the form bottom is likewise detached from the spacers which are left in place. It is not necessary, as has been the case with previous devices to clip or shear off projecting bolts, but in this instance the fastening bolts need simply to be unscrewed and they can then be readily removed from the concrete encasement along with the forms. Not only do the parts remaining in the concrete form a suitable point of attachment for subsequent structures but they also render the removal of the forms themselves quite simple.

I claim:

A form hanger for use with any one of a plurality of different beams comprising a form bottom, a spacer interposed between said form bottom and any selected one of said beams, a hooked bolt engaging said selected one of said beams and piercing said spacer, means within the confines of said spacer for clamping said spacer and said bolt on said selected one of said beams, and means for clamping together said spacer and said form bottom.

In testimony whereof, I have hereunto set my hand.

GEORGE E. GREENWOOD.
